(57) **CLAIM**

What is claimed is the ornamental design for a riser for rail mounted optics, as shown and described.

DESCRIPTION

FIG. 1 is an elevated front left side perspective view of a riser for rail mounted optics showing my new design with an internal storage compartment clocased by a removable cap. FIG. 2 is an elevated rear left side perspective view of the riser of FIG. 1, showing the cap removed from the storage compartment.

FIG. 3 is a depressed rear right-side view of the riser of FIG. 1.

FIG. 4 is a left side elevational view of the riser of FIG. 1.

FIG. 5 is a front elevational view of the riser of FIG. 1.

FIG. 6 is a rear elevational view of the riser of FIG. 1.

FIG. 7 is a top plan view of the riser of FIG. 1.

FIG. 8 is a bottom plan view of the riser of FIG. 1.

FIG. 9 is a right-side elevational view of the riser of FIG. 1; and,

FIG. 10 is another right-side elevational view of the riser of FIG. 1, showing the riser attached to a firearm and a rail mounted optic attached to the riser, the firearm and the rail mounted optic forming no part of the invention.

The dashed lines in the figures and the gray shaded area within the dashed lines depict portions of the riser that form no part of the claimed design. The dash-dot-dashed lines in the figures depict environmental structures that form no part of the claimed invention.
